(57) **CLAIM**

The ornamental design for a topper for a vehicle dashboard, as shown and described.

DESCRIPTION

FIG. 1 is a perspective view of a topper for a vehicle dashboard showing my new design;

FIG. 2 is a top view of a topper for the vehicle dashboard;
FIG. 3 is a bottom view thereof;

FIG. 4 is a rear view thereof;

FIG. 5 is a front view thereof;

FIG. 6 is a left side view thereof; and,

FIG. 7 is a right side view thereof.

The broken lines illustrate portions of the topper for a vehicle dashboard that form no part of the claimed design.
